UNITED STATES PATENT OFFICE.

STEPHEN NEWCOMBE WELLINGTON, OF LONDON, ENGLAND, ASSIGNOR TO COALITE LIMITED, OF LONDON, ENGLAND.

FURNACE-SETTING FOR THE DESTRUCTIVE DISTILLATION OF COAL OR OTHER CARBONACEOUS SUBSTANCES.

1,234,517.

Specification of Letters Patent. Patented July 24, 1917.

Application filed May 17, 1916. Serial No. 98,226.

To all whom it may concern:

Be it known that I, STEPHEN NEWCOMBE WELLINGTON, a subject of the King of Great Britain and Ireland, residing at 39 Mincing Lane, London, E. C., England, have invented certain new and useful Improvements Relating to Furnace-Settings for the Destructive Distillation of Coal or other Carbonaceous Substances, of which the following is a specification.

This invention relates to furnace settings for the destructive distillation of coal or other carbonaceous substances and especially to that type of furnace settings where vertical retorts are employed which are charged at the top and discharged at the bottom, and where the retorts are of an oblong section; and the invention has for its object to effect the heating of the retorts uniformly and with efficiency and in such manner that the temperature conditions throughout may be precisely regulated according to the character of the residue and by-products required.

The respective retorts which are formed of an oblong cross section and tapered outwardly toward the bottom are set in a known manner between series of horizontal partitions which form a vertical series of horizontal chambers beside and between the respective retorts and extend from one wall of the setting to the other. These chambers are provided according to the invention with two thin vertically disposed partitions by which a central combustion space is formed between them by which the heating gases are compelled to take a tortuous path, that is to traverse the length of the horizontal chamber to and fro so that thus the heating gases pass through a comparatively narrow space beside the retort before being discharged. Two such thin vertical partitions are provided in each horizontal chamber so that thus a mixture of gas and air may pass between the respective two partitions of each set and on reaching the end of the partitions opposite to that at which the mixture of gas and air is admitted, the gases may return and pass on the outer side of each of the partitions along the lateral spaces between the respective partitions and the adjacent retorts. The heating gases are thus directed in contact with the outer surface of

the retort and the circulation of the gases takes place within one plane. 55

According to the invention moreover, I provide adjacent the series of retorts, a series of substantially vertical exhaust flues corresponding in number to the number of retorts in the setting and into which exhaust flues the gases from the horizontal chambers at the sides of the respective retorts discharge and I provide also a series of substantially vertical air flues in the setting from each of which air may pass into the 60 horizontal chambers of the respective vertical series.

A recuperator or regenerator is provided advantageously beneath the setting and passages are formed or a chamber is provided 70 in the setting through which the air may pass before entering the respective vertical air flues, the construction of the chamber or passages being such that the walls thereof are heated by the exhaust-gases passing out; or instead a regenerator may be provided 75 in which the flow of air and the exhaust gases may be reversed in the regenerator. In such a modification, however, it will be understood that the waste gases will always 80 pass through the vertical series of exhaust flues and the air through the vertical series of air flues, and by such means the flow of gases for heating the retorts remains in the same direction. 85

The invention comprises the construction which is hereinafter described with reference to the accompanying drawings.

In the drawings,

Figure 1 is a sectional plan view of the 90 furnace setting taken on the line E, F of Fig. 2,

Fig. 2 is a vertical section on the line A, B of Fig. 1,

Fig. 3 is a compound vertical section on 95 the line C, D of Fig. 1, and

Fig. 4 is a vertical section on the line G, H of Fig. 1.

In carrying the invention into effect according to one construction I provide a 100 series of vertical retorts *a* of oblong section within a setting in the lower part of which a regenerator or recuperator *b* is provided, and I provide beside and between the respective vertical retorts a vertical series of 105 horizontal partitions *b* without necessarily

providing any port or passage for communication between the horizontal chambers thus formed or other communication between adjacent horizontal heating chambers in the same plane, and I provide within each horizontal chamber two thin vertical partitions *c* which form a central combustion space comparatively wide extending the length of the retort into which at one end the supply of 10 gas and air passes for combustion therein. The vertical partitions, however, extend at the other end of the heating chamber opposite to that at which the gas and air enter a little short of the extreme end wall so that 15 thus a space is formed at that end into which the gases may discharge and return in the opposite direction through the narrower lateral spaces *c*¹ formed by the partitions on each side of the central space.

20 A damper block *c*² of angular form may be provided at the end of the heating chamber at which the gases discharge from the central combustion space. Such damper blocks present their inclined faces to the 25 current of gases so that thus the inclined faces serve to deflect the gases while the damper block serves at the same time to regulate the outflow according to the position in which it is placed with respect to the 30 ends of the partitions *c*.

The respective vertical partitions *c* referred to are provided of the same refractory material as that of which the horizontal partitions *b* are provided or they may be 35 formed as a tube of a square or other suitable section so as to divide the heating chamber by substantially vertical walls into three spaces on each side of the retorts.

The gas may be led into the central combustion space through a horizontal pipe *d* extending through the setting at one side, the gas pipe for each chamber of the vertical series being connected to a substantially vertical service pipe *d*¹ mounted on the exterior wall of the setting. An air passage 40 *e* is also provided horizontally in the setting for leading air to each of the combustion spaces, and the air passage for each heating chamber of the vertical series communicates with the respective vertical air 45 flues *f* and air advantageously may be led from adjacent vertical air flues *f* from each side into the respective horizontal air passages *e*, and the ports *g* through which the 50 air is admitted to the respective horizontal passages may be regulated by means of sliding dampers *g*¹ or other suitable means.

As the greater thickness of the charge of coal in the lower ends of the tapered retorts necessitates the expenditure of more heat in distillation than at the upper and thinner portion of the charge, the gas pipes *d* of the lower heating chambers are provided of greater capacity than those of the upper 60 heating chambers.

The horizontal air passages *e* may be formed as tubes of metal or they may be formed of refractory material, while the corresponding gas pipe for each air passage may pass centrally therethrough and the horizontal air passage may extend to the outer wall of the casing where a valve plate *h* may be mounted.

A series of vertical exhaust flues *i* is built in the setting adjacent the heating chambers, and ports *j* are provided in the intermediate wall through which the gases may discharge from the lateral spaces of the heating chambers into the adjacent exhaust flue. It will be understood that in such an 80 arrangement the series of vertical air flues is arranged adjacent to the exhaust flues and the respective exhaust and air flues are arranged in line.

With respect to other constructional features the construction and arrangement of the furnace setting is substantially the same as that described in the specification filed pursuant to the prior application No. 53,631 90 of 1915.

I claim:

1. In a furnace setting for vertical retorts for the destructive distillation of coal and other carbonaceous substances, vertical retorts of an oblong section in horizontal 95 plan, a series of horizontal partitions in the setting adjacent the sides of the said retorts, the said horizontal partitions thus forming a series of separate heating chambers on each side of the respective retorts, and two vertical partitions in the respective heating chambers thus formed, reaching from one end of the respective heating chambers to a point short of the extreme end thereof by which a tortuous path is presented for the 100 heating gases, substantially as described.

2. In a furnace setting for vertical retorts for the destructive distillation of coal and other carbonaceous substances, vertical retorts of an oblong section in horizontal 110 plan, a series of horizontal partitions in the setting adjacent the sides of the said retorts, the said horizontal partitions thus forming a series of separate heating chambers on each side of the respective retorts, two vertical 115 partitions in the respective heating chambers thus formed, reaching from one end of the respective heating chambers to a point short of the extreme end thereof by which a tortuous path is presented for the heating 120 gases, vertical exhaust flues corresponding in number to the number of retorts in the setting and a corresponding series of vertical air supply flues from which air may pass into the heating chambers aforesaid, and a 125 recuperator or regenerator with which said exhaust and air supply flues are in communication, substantially as described.

3. In a furnace setting for vertical retorts for the destructive distillation of coal 130

and other carbonaceous substances, vertical retorts of an oblong section in horizontal plan, a series of horizontal partitions in the setting adjacent the sides of the said retorts, the said horizontal partitions thus forming a series of separate heating chambers on each side of the respective retorts, two vertical partitions in the respective heating chambers thus formed reaching from one end of the respective heating chambers to a point short of the extreme end thereof

by which a tortuous path is presented for the heating gases, and angular damper blocks in the said heating chambers in position beyond and between the respective vertical partitions, said angular damper blocks being movable, substantially as described.

STEPHEN NEWCOMBE WELLINGTON.
